UNITED STATES PATENT OFFICE.

JOHN P. NEFF, OF EAST ORANGE, NEW JERSEY, ASSIGNEE, BY MESNE ASSIGNMENTS,
TO AMERICAN ARCH COMPANY, OF NEW YORK, N. Y., A CORPORATION OF DELA-
WARE.

STEAM-BOILER.

1,138,057.

Specification of Letters Patent.

Patented May 4, 1915.

Application filed May 12, 1913. Serial No. 767,055.

To all whom it may concern:

Be it known that I, JOHN P. NEFF, a citizen of the United States, and a resident of East Orange, county of Essex and State of New Jersey, have invented certain new and useful Improvements in Steam-Boilers, of which the following is a specification.

My invention relates to improvements in locomotive boilers and has particular reference to improvements in locomotive fire boxes of the extended combustion chamber type.

The object of my invention is to increase the efficiency of locomotive fire boxes of the extended fire box type; to increase the interior radiating surface through which the heat of combustion may be transmitted to the water of the boiler; to increase the circulation of water in the boiler; and to increase the admixture and commingling of the gases of combustion as they flow from the fuel bed to the flues.

My invention consists in a locomotive fire box which has a barrel-like extension at its forward end and which is provided with a number of water-circulating tubes which rise from the lower portion of the extension and extend rearwardly and upwardly to the rear sheet of the fire box.

My invention further consists in a fire box of the extension type, provided with a refractory baffle arranged between the grate and the flue sheet and dividing the fire box into a main and an auxiliary combustion chamber, the baffle comprising a wall arranged within the extension of the fire box in combination with an inclined refractory arch supported in position by water circulating tubes which extend from the lower part of the extension upwardly and rearwardly through the fire box to the rear end thereof, said arch having its forward end arranged against the upper part of the transverse wall.

My invention further consists in a locomotive boiler fire box of the extension type in combination with a transverse vertical refractory wall arranged within the rear end of the fire box extension, a transversely extending longitudinally inclined arch or baffle in the fire box, with its forward end arranged against the upper part of the wall and inclined water circulating tubes extending from the lower part of the extension upwardly and rearwardly through the fire box and upon which the inclined arch is sup-

ported, the arch being composed of wedge shaped bricks arranged on and between the tubes.

My invention further consists in the various features of construction and the combination and arrangements of parts, whereby the above and other objects are attained, and all as hereinafter described and particularly pointed out in the appended claims.

My invention will be more readily understood by reference to the accompanying drawings in which:

Figure 1 is a central longitudinal sectional view of a locomotive boiler fire box having an extension at its forward end and provided in accordance with my invention with a plurality of water-circulating tubes; Fig. 2 is a vertical transverse sectional view of the fire box on the line 2—2 of Fig. 1; Fig. 3 is a view similar to Fig. 1, but showing a modified form of tube; and Fig. 4 is a transverse section of the arch on the line 4—4 of Fig. 3.

In order to obtain sufficient fire box space without making the fire box too wide, some locomotive fire boxes are extended forwardly within the barrel of the boiler, the flue sheet in such instances being set forward in the boiler beyond the forward end of the grates. This construction provides a water space between the extended end or combustion chamber of the fire box and the lower outside sheet of the boiler and I connect this water space with the upper part of the rear water leg of the boiler with water circulating tubes, arranging them in such manner that they materially add to the efficiency of the boiler as a means for converting the water in the boiler into steam.

A locomotive boiler fire box of the type to which my invention relates, and as illustrated in the drawings, is made up of a fire box proper A, above the grate B, and an extension combustion space C within the barrel portion D of the boiler. The two combustion spaces A and C complete the fire box space and this space is inclosed by the flue sheet E at the forward end, the rear sheet F at the rear end, side sheets G, and the crown sheet H, the crown sheet extending from the rear sheet to the flue sheet. The lower part of the extension or combustion chamber C of the fire box is completed by a curved sheet J which follows in a general way the curvature of the outer shell of the boiler. The sheet J is spaced from the outer sheet of the

boiler and provides a water space K between the floor of the combustion chamber C and the outer sheet D^x of the boiler which is substantially uniform in radial depth.

5 One of the purposes of my invention is to provide a circulation within the boiler from the space below the fire box extension to the rear end of the fire box and to do this I provide a number of water circulating tubes L which rise from the floor portion of the extension C and lead upward and rearward to the upper part of the rear end of the fire box. These tubes not only add to the steaming qualities of the boiler by reason 10 of the rapid circulation of the water in the boiler which is set up through them, but the tubes themselves add materially to the radiating surface of the fire box through which the heat of combustion is transmitted to the water. The tubes L are preferably curved or bent at their forward ends on relatively large radii as indicated at L^x, this construction serving to raise the tube proper to a suitable height above the grate so that the 15 refractory arch M will be supported at a proper height above the grate to afford a suitable combustion space between the arch and grate. As indicated in Fig. 2 the forward end L² of the tube is bent or formed in such a manner that it is caused to enter the sheet J substantially at right angles to the surface of the sheet at the point at which it enters. This is for the purpose of providing a construction wherein the tube can be 20 most readily, easily and properly secured, steam and pressure tight, in the sheet J.

In order to afford access to the end of the tube for the purpose of securing it in the sheet by expansion and beading, similar to the ordinary manner in which a boiler flue is secured in a flue sheet, I provide an opening D¹ in the sheet D located opposite to and directly in line with each of the ends L² of the tubes L, and I preferably close these 25 openings by means of screw plugs D². It will be understood that by removing the plugs D², the proper tool can be inserted into the boiler through the opening D¹ to expand the end of the tube and properly secure 30 it in the boiler sheet J.

To prevent the direct flow of the gases of combustion from the fuel bed to the flues and to cause their efficient intermingling and intermixing, I interpose a refractory baffle 35 in the path of the gases consisting of a transverse refractory wall N arranged at the rear end of the auxiliary combustion chamber C and the refractory arch M extending rearwardly from the upper end of the wall, and 40 I support the wall M upon the tubes L. The wall N rises to a point slightly below the middle of the height of the auxiliary combustion chamber and adjacent to the forward end of the grate, and I provide it with 45 suitable openings to receive the tubes L

which pass through the upper part of the wall, the wall is thus braced or stayed in position by the tubes and the tubes are held against lateral displacement by the wall.

In the form of construction illustrated in the drawings, the upper ends of the curved parts L^x of the tubes project through the upper part of the wall N, and, as the tubes at this point are inclined upwardly and rearwardly at quite a sharp angle, they serve to 15 brace the wall end against movement forwardly in the fire box.

As shown in the drawings, the wall is built up of two transverse rows of bricks n¹ and n², the lower row n¹ being composed of several individual bricks which are conformed on their lower edges to the curvature of the floor of the auxiliary combustion chamber C and are provided on their lower edges with projections n³ adapted to 30 interlock with the floor of the combustion chamber C to hold this lower row of bricks in place. The joint a¹, by which the lower sheet c¹ of the combustion chamber C, and the sheet a² forming the forward end of the 35 fuel space, are jointed, provides the necessary projections to interlock with the bricks n¹.

In the form of my invention illustrated in the drawings, the arch M is built up of a 40 plurality of transverse rows of refractory arch bricks m. These bricks extend between and are supported upon the tubes and are provided at their ends with sockets or grooves m¹ adapted to receive the tubes. 45 In a sense, the bricks are wedgingly interposed between the tubes and their weight tends to spread the tubes apart but the tubes are effectually prevented from spreading by their interlockment with the wall N.

Between the outermost tubes and the adjacent side sheets, I sometimes place marginal bricks which I place in upwardly and outwardly inclined positions, wedgingly engaging the side sheets and thus completing the arch, the wall N effectually separates the lower part of the auxiliary combustion chamber C from the main combustion chamber A, and the refractory arch M prevents the direct flow of gases of combustion 50 to the upper part of the auxiliary combustion chamber. The complete baffle thus causes the gases of combustion from the forward end of the fuel bed to flow toward the rear end of the fire box and in contact with the interior surface thereof before they can 55 flow to the forward end and into the auxiliary combustion chamber C. This deflection of the gases causes an intermingling and a breaking up of the several strata and results in the practically perfect oxidation 60 of all of the fuel before the gases of combustion escape through the flues. The interlocking of the tubes L with the wall N serves 65 to hold the tubes against displacement or 70

bending, both vertically and transversely, which might be caused by the weight of the arch M. Furthermore the weight of the arch M serves to hold the wall N in position, 5 for the arch M being arranged in an upwardly inclined position upon the tubes L it presses against the upper part of the wall and locks it against the curved portions L' of the tubes L.

10 In Fig. 3 I have shown a slight modification of my invention which varies from the preferred form in that the tubes instead of being curved on long radii, as shown in Fig. 1, are deflected or formed on substantially 15 straight lines connected by curved portions. The tubes rise as in the former instance at right angles to the floor of the auxiliary combustion chamber, and are thence bent rearwardly on an angle of about 45°, as 20 shown at O, Fig. 3. After they have risen to the desired height, as indicated at P, they are inclined rearwardly and upwardly to the rear sheet of the boiler in a position to properly support the arch M, and they also 25 serve to hold the wall N in position. In this form the holes which are provided in the wall N to receive tubes can be made on straight lines instead of curved lines and are hence somewhat easier to produce.

30 As many modifications of my invention will readily suggest themselves to one skilled in the art, I do not limit or confine my invention to the particular structures and forms herein shown and described.

35 I claim:

1. In a locomotive boiler, a fire box having a barrel-like projection extending into the body of the boiler from the forward end of the fire box and serving as an auxiliary 40 combustion chamber, in combination with water-circulating tubes extending longitudinally through the fire box rising from the lower portion of the extension and extending thence rearwardly and upwardly to the 45 rear end of the fire box, a refractory transverse wall arranged at the rear end of the auxiliary combustion chamber and a refractory arch composed of refractory bricks supported by and wedgingly engaging the 50 tubes and extending from the rear face of the wall, said wall serving to brace the tubes against the wedging action of the arch bricks.

55 2. In a locomotive boiler the combination with a fire box having an auxiliary combustion space extending forward into the barrel of the boiler beyond the front water leg and closed at its forward end by the flue sheet, a refractory baffle wall closing the lower part 60 of the mouth of said extension and water circulating tubes rising from the floor of the extension between the wall and the flue sheet and extending rearwardly and upwardly

through the fire box and through said refractory wall as and for the purpose specified. 65

3. In a locomotive boiler having a fire box of the extension combustion chamber type closed at its forward end by the flue sheet, a refractory baffle wall arranged in 70 the mouth of said extension and partially closing the entrance thereto, and water circulating tubes rising from the floor of the extension between the baffle wall and the flue sheet and extending rearwardly and upwardly through the fire box and through the upper part of said refractory wall, as and for the purpose specified. 75

4. In a locomotive boiler the combination with a fire box of the extension combustion 80 chamber type of longitudinally arranged water circulating tubes extending from the lower part of said extension and inclined upwardly and rearwardly through the fire box, a refractory baffle wall resting upon the 85 floor of said extension and arranged substantially above the front water leg of the fire box and engaging said tubes above their lower ends whereby the tubes and the wall mutually support each other. 90

5. In a locomotive boiler having a fire box of the extension combustion chamber type closed at its forward end by the flue sheet, a refractory baffle supported in the mouth 95 of said extension and partially closing the entrance thereto, water circulating tubes rising from the floor of the extension between the baffle wall and the flue sheet and extending rearwardly and upwardly through the fire box and through the upper part of said refractory wall, and a rearwardly inclined refractory front arch supported by and upon the tubes, the forward end of the arch resting against the upper part of said baffle wall whereby the arch is held in position. 100

6. In a locomotive boiler in combination with a fire box of the extension combustion chamber type, of longitudinally arranged water circulating tubes extending from the lower part of said extension and inclined upwardly and rearwardly through the fire box, a vertical refractory wall resting upon the 110 floor of said extension arranged substantially above the front water leg of the fire box and engaging said tubes above their lower ends, and an inclined arch supported by and upon said tubes extending from side sheet to side sheet and held in position by said wall. 115

In testimony whereof, I have hereunto set 120 my hand, this 5th day of May, 1913, in the presence of two subscribing witnesses.

JOHN P. NEFF.
